COLLAPSIBLE TUBE CLOSURE

Herman Renicke, St. Louis, Mo.

Application March 10, 1936, Serial No. 68,097

1 Claim. (Cl. 221—60)

My invention relates generally to closure means for collapsible tubes to replace the usually present caps thereof, and an important object of my invention is to provide a new and novel construction of closure whereby the contents of the collapsible tube may be quickly and easily availed of, and wherein means is provided to prevent waste of the contents, and to preserve the contents against contamination and contact with the atmosphere while the closure is in a closed condition.

Another important object of my invention is to provide closure means of the character indicated above wherein spring-pressed means is utilized to actuate a portion of the device into operative position upon the performance as a condition precedent to such operation, of an unlocking or unlatching operation which is performed manually.

Another important object of my invention is to provide in closure means of the character indicated above, positive locking means which locks the closure securely in closed position.

Other important objects of my invention will be apparent from a reading of the following description in connection with the drawings, wherein for purposes of illustration I have shown a preferred embodiment of my invention.

In the drawings:—

Figure 1 is a transverse vertical sectional view taken through an embodiment of the invention.

Figure 2 is a view similar to Figure 1 but showing the dispensing tube in elevated open position.

Figure 3 is a horizontal sectional view taken through Figure 1 approximately on the line 3—3 and looking downwardly in the direction of the arrows.

Figure 4 is a top plan view of Figure 2.

Figure 5 is a perspective view of the dispensing tube and the locking disk.

Figure 6 is a perspective view showing the top of the embodiment with the locking ears in locking position.

Figure 7 is a transverse vertical sectional view taken through the dispensing tube or cylinder.

Figure 8 is a transverse vertical sectional view taken through the locking disk.

Referring in detail to the drawings, the numeral 5 generally designates a conventional form of collapsible tube, such as a collapsible tube containing toothpaste or the like, the said tube having the exteriorly threaded neck 6. In accordance with the present invention I provide for engagement with the threaded neck 6 the cap 7 which is generally designated 7 and which is

generally cylindrical in form and is interiorly threaded at its lower end as indicated by the numeral 8 for engagement with the threads of the neck 6 of the collapsible tube 5.

The cap 7 extends axially with respect to the collapsible tube neck 6 and rises considerably above the neck 7 and is provided at its upper end with the radially inwardly extending flange 9 which defines the opening 10 and the radially outwardly extending flange 11 which may be knurled if desired, for easy application to the neck of the collapsible tube. The flange 11 also lends rigidity to the cap 7.

On the top of the cap 7 are diametrically opposed radially inwardly leaning locking lugs 12 and 13 under which are adapted to be rotatably placed the radial diametrically opposed lugs 14 and 15 which are formed on the edge of the locking disk which is generally designated 16, whereby movement of the locking disk 16 in an axial direction with respect to the cap 7 is positively prevented.

The locking disk 16 is circular in form and is flat to rotatably slide on the top of the cap 7, and the center of the disk 16 is punched up as indicated by the numeral 17 to provide a female receptacle for the snap-button 18 which is arranged on the center of the top 19 of the dispensing cylinder 20. The receiver 17 on the locking disk 16 is adapted when pressed down upon the male snap-button 18, to snap into securing engagement with the snap-button 18.

The dispensing cylinder 20 is tubular in form and close to but spaced from its lower end is the outwardly pressed generally triangular cross section flange or annulus 21. The lower end of the dispensing cylinder 20 is disposed to be approximately flush with the axially inward end of the collapsible tube neck 6 when the cylinder is in the closed position, and the lower end of the cylinder is open. The flange or annulus 21 is arranged at such a height on the cylinder 20 as to engage or almost engage the axially outward end of the neck 6 of the collapsible tube, so as to act as a closure against the passage between the interior of the neck 6 and the exterior of the cylinder 20 of any fluid material in the collapsible tube, while the cylinder 20 is in the closed position illustrated in Figure 1.

The opening 10 in the top of the cap 7 closely fits the exterior of the uniform diameter cylinder 20 so that the cylinder 20 is closely slidably there-in in the position illustrated in Figures 1 and 2. A helical spring 22 is circumposed on the cylinder 20 so as to act between the underside of the top 55

of the cap 7 and the upper side of the flange 21 of the cylinder 20, so as to normally urge the cylinder 20 in an axially inward direction from the open position shown in Fig. 2. It is to be observed that the lower part of the cylinder 20 below the flange 21 is closely slidably in the neck of the collapsible tube.

When the lugs 14 and 15 of the locking disk 16 have been moved from a position under the bosses 12 and 13 on the top of the cap 7, the spring 22 will simply hold the cylinder 20 down in the closed position illustrated in Figure 1, and the same position of the cylinder 20 will be brought about by the spring 22 while the lugs 14 and 15 of the locking disk are disposed under the bosses 12 and 13 on the top of the cap 7.

The open position of the cylinder 20, illustrated in Figure 2, is achieved by disengaging the lugs 14 and 15 of the locking disk from the bosses 12 and 13 on the top of the cap 7 and then pulling the cylinder upwardly or axially outwardly so as to bring the dispensing opening 24 which is in the side wall of the cylinder 20 to a position above the top of the cap 7, against the resistance of the spring 22, whose compression in such a position is clearly illustrated in Figure 2. The lower part of the cylinder 20 below the flange 21 is sufficiently long to remain telescoped in the axially outward end of the collapsible tube neck even in the full extreme open position of the cylinder 20.

As soon as the hand or other operating agency has been removed from the cylinder 20 or from the locking disk 16, by reason of which the cylinder was held in the open position, the spring 22 will expand and draw the cylinder 20 down into the closed position illustrated in Figure 1, in which position of the cylinder 20, the locking disk 16 may be rotated so as to bring the lugs 14 and 15 under the bosses 12 and 13, and thereby positively lock the cylinder 20 in its closed position. If desired the locking disk 16 may be dispensed with simply by snapping the same from the cylinder 20 in the manner of disconnecting one-half of a snap-button from the other half. For accurate and convenient operation, there is provided on the locking disk 16 an arrow 25 which indicates the location of the dispensing opening 24 in the side of the cylinder.

Although the cylinder 20 may be operated to the open position by grasping the same or by

pulling on the locking disk 16, the described arrangement is more properly intended to be operated simply by squeezing the body of the collapsible tube, the doing of which will exert sufficient pressure on the contents of the collapsible tube, to force said contents out of the neck of the tube with force adequate to extend the cylinder 20 to the open position, provided the locking disk is in an open position. When the squeezing pressure on the body of the collapsible tube has been released, the spring 22 is sufficiently strong to bring the cylinder 20 into its closed position; so that the device of the invention may be said to be automatic closing in operation and automatic opening in operation. When the lugs of the locking disk are engaged with the bosses on the top of the cap 7, no amount of exertion of pressure ordinarily encountered, upon the body of the collapsible tube will effect opening of the cylinder.

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claim.

What is claimed as new is:—

A closure for a collapsible tube having a neck, said closure comprising a cap removably secured on said neck, a dispensing tube slidably in said cap and arranged to have an open position wherein a dispensing opening formed in the side of the dispensing tube is exposed exteriorly of said cap, and spring means for returning said dispensing tube to closed position wherein said dispensing opening is located within said cap, a locking plate on the outward end of said dispensing tube, and having a recess in its underside, said recess being formed with a restricted opening, locking lugs on the edge of the plate, keeper means on said cap with which said lugs are engageable to hold said dispensing tube in the closed position, and snap-button connection means connecting said locking plate on said dispensing tube and comprising a stud on the tube for insertion in the recess on the plate to secure the plate for rotation on the tube.

HERMAN RENICKE.
